UNITED STATES PATENT OFFICE.

ARTHUR REGINALD ANGUS, OF LONDON, ENGLAND.

RAILWAY SAFE-RUNNING DEVICE.

Application filed April 14, 1913. Serial No. 761,043.

To all whom it may concern:

Be it known that I, ARTHUR REGINALD ANGUS, a subject of the King of Great Britain, and residing at the Royal Automobile Club, Pall Mall, London, S. W. 1, in the county of London, England, solicitor, have invented a certain new and useful invention entitled Improvements in or Relating to Railway Safe-Running Devices, of which the following is a specification.

This invention relates to electrical train protecting apparatus and comprises the various features hereinafter set forth in the claiming clauses hereof.

The invention is illustrated by the accompanying drawings, which represent by way of example apparatus constructed and arranged in accordance therewith.

Fig. 1 is a diagrammatic representation of the apparatus on a locomotive.

Fig. 2 shows track apparatus so constructed that a signalman can exercise a selective control over the passage of trains through a section, but cannot introduce a risk of collision by erroneous operation of his switch.

On or about the railway track there are placed track contacts each of which consists of some suitable non-conductive material such as wood or the like, and has a top contact plate of some suitable conducting material. The ends of each track contact are ramped so as to enable a contacting device on a train to come into contact with a track contact without the risk of being broken.

Each track contact is bolted or otherwise firmly affixed to the sleepers on or about the railway track and is preferably placed midway of the track rails.

The track contacts are divided into what I call warning contacts, and stop contacts, the warning contacts and stop contacts being adapted to effect different displacements respectively of a contacting device on a train.

In order to effect these different displacements the track contacts may be so constructed that the highest part of the top surface of each of the stop contacts is higher above the top surface of the railway track rails than is the highest part of the top surface of each of the said warning contacts above the top surface of the railway track rails.

A suitable contacting device comprising a shoe 10 (Fig. 1) is attached to, and insulated from, any suitable part of a locomotive or brakevan or other suitable vehicle. The

shoe 10 is adapted to be given different displacements by contact with track contacts such as 1, 2, 3, 4, 5, and 6, (Fig. 2) placed on or about, or above, the railway tracks and, when not in contact with a track contact, is returned to its normal position by gravity and by a spring 7, although it may be returned to its normal position by one or more springs only or by gravity only. Attached to, and insulated from, the contact shoe 10 is a resilient bridging contact member 8 comprising fingers adapted to bridge, when the shoe is in its outmost position (hereinafter referred to as "its lowest position"), the contact plates 9, 11, 12, so as to complete the circuits of the generator 14 by wire 15, contacts 16 and 17, wire 18, contact plate 9, bridging member 8, and thence by (a) contact plate 11, wire 19, coil of solenoid 20, contacts 31 (if bridged by handle 30) and wire 21 back to the generator, thereby energizing solenoid 20 and holding closed the valve 22 controlling means either for shutting off the motive power of the locomotive, or for applying the brakes on the train, or both; and by (b) contact plate 12, wire 23, coils of solenoid 24 and magnet 29, contacts 31 (if bridged by the lever 30), and wire 21 back to the generator 14, thereby energizing the solenoid 24 and keeping closed the valve 25 so as to prevent the danger whistle 26 from being blown, and also energizing the magnet 29 and attracting its armature so as to maintain the miniature visual signal 28 in the clear, or off, position.

When the shoe 10 comes into contact with a warning contact such as 1 or 6 it is raised to such an extent that one of the bridging contact fingers passes off the contact plate 12 thereby breaking there, as far as the bridging contact member 8 is concerned, the connexion between the contacts 9 and 12, and so opening the circuit relating to the solenoid 24 and magnet 29, so that, if the said circuit is not otherwise maintained, the plunger of the solenoid 24 is forced out by whatever pressure may be acting on the valve 25 and the danger whistle 26 is blown and the miniature signal 28 is also raised into the on, or danger position.

When the shoe 10 comes into contact with a stop contact such as 2, or 5, it is displaced to a greater extent than when it comes into contact with a warning contact so that the bridging contacts are also raised clear of the contact plates 9 and 11, thereby breaking

the circuit of the solenoid, 20, so that, if the said circuit is not otherwise maintained, the plunger of the solenoid 20 is forced out by whatever pressure may be acting on the valve 22 and the lever 30 (used for replacing the plunger) is moved so that the circuits of the generator 14 and the coils of solenoids 20 and 24, and magnet 29 are broken at the contacts 31.

- 10 It is intended that the opening of the valve 22, which is normally held closed by the plunger of the solenoid 20, should allow the admission of fluid pressure such as of steam, air, gas, or the like, to a suitable cylinder, the piston of which is adapted to shut off the motive power (such as steam or the like) of the locomotive and should also allow or cause the operation of means for applying the brakes on the train.
- 15 20 Either the shutting off of the motive power, or the application of the brakes, or both, may be used for stopping the train.

If the commutator switch 100 and the reversing gear switch 41 are in the positions 25 shown in Fig. 1—that is to say in the positions for the down journey—when the shoe 10 comes into contact with either a warning or a stopping track contact which has been rendered electrically conductive in the manner hereinafter explained, current will flow from the generator 32 on the locomotive, by wire 33, coils of magnet 34, wire 35, arm 36 and contact 37 of the commutator switch 100, wire 42, arm 43 and contact 44 of the 30 reversing gear switch 41 (which is adapted to move with the reversing lever of the locomotive,) wire 48, shoe 10, the track contact, and thence through a track circuit, back by earth and the rails to the frame of 35 the locomotive, wire 49, contact 46, and the arm 45 of the reversing gear switch, wire 50, contact 39 and arm 38 of the commutator switch, and wire 51 to the generator 32.

If the conditions of the circuits and apparatus connected thereto are normal the current which flows will be of normal value and will cause the coils of the magnet 34 to attract the armature 52, against gravity and the spring 53, so as to contact with the 45 insulated contacts 54 and 55, and at the same time to break contact with contact 56.

50 By a current of predetermined normal value is meant one which is sufficient, on energizing the magnet 34, to attract its armature 52 so as to contact with the contacts 54 and 55 but is not sufficient to break contact between the contacts 16 and 17 by lifting the pivoted lever 70 against gravity and a 55 spring 71.

60 65 Contact of the armature 52 with the contacts 54 and 55 provides paths, in substitution for those broken at contact plates 9, 11, and 12, through branch wire 57, armature 52, contacts 54 and 55, and wires 58 and 59 respectively, to the coils of solenoid

20, and solenoid 24 and magnet 29, so that warning and stopping operations on the train are restrained. At the same time the circuit of the coils of solenoid 60, which is normally completed from generator 14, by 70 wire 15, contacts 16 and 17, wire 18, branch wire 57, armature 52, contact 56, wire 61, coils 60 and wire 21 is broken at the contact 56, thus de-energizing the solenoid 60 and allowing its plunger to be forced out by whatever pressure may be acting on the valve 62 so that the line clear whistle 63 is blown.

75 From the foregoing description it will be seen that the apparatus on the locomotive comprises two generators 14 and 32 (though if desired a common generator may be used); an electromagnet 34 adapted when normally energized to complete substitutional circuits through the normally energized restraining coils 24, 29 and 20, and at 80 the same time to break the circuit of the coil of the solenoid 60; a commutator switch 100, and a reversing gear switch 41 which is adapted to be operated by the movement of the reversing gear of the locomotive and which when in the position shown in Fig. 1—that is to say, for the down journey—and when the commutator switch is also in the position shown, connects the positive pole 85 of the generator 32, through the electromagnet 34, to the shoe 10, and the negative pole of the generator 32 to the frame of the locomotive and so to the rails and earth.

90 When the reversing gear switch is moved over for the locomotive to run on the up 100 journey the connexions of the poles of the generator 32 to the shoe 10 and to the frame of the locomotive are reversed, that is to say, the shoe 10 is connected to the negative pole 105 of the generator and the frame of the locomotive to the positive pole of the generator through the electromagnet 34 and at the same time a resistance 64 is inserted into the circuit.

110 The commutator switch 100, which must be operated when the locomotive is turned round on a turntable, loop, triangle, or the like, performs functions similar to those of the reversing gear switch 41, that is to say, reverses the connexions of the generator 32 115 to the shoe 10 and to the frame of the locomotive and at the same time inserts a resistance 65 into the circuit. Means for automatically compelling a driver to move the commutator switch 100 in order to avoid 120 an automatic stop are described in the specification of my application for Letters Patent No. 761042 of even date herewith.

125 When the commutator switch 100 and the reversing gear switch 41 are both moved over from the positions shown in Fig. 1, the locomotive apparatus will be set for running in the same direction as when in their present positions—that is to say for the down journey, but in this case both of the resist- 130

- ances 64 and 65 (which are equal) would be in the circuit in series when there should be no resistance at all in the circuit. For this reason insulated short-circuiting plates 5 are placed on the arms of these two switches which, when both the switches are over, short-circuit the resistances 64 and 65 by contact with suitable contacts 66, 67, 68, and 69.
- 10 It will thus be seen that a locomotive running on the down journey will always have its contact shoe 10 connected to the positive pole of the generator and also that both the resistances 64 and 65 will be short-circuited 15 but that for the up journey the shoe 10 will always be connected to the negative pole of the generator and one or the other of the resistances 64 and 65 will always be connected effectually in circuit.
- 20 When a current exceeding the predetermined normal value flows through the coils of the electromagnet 34, the armature 52 is attracted with sufficient force against the insulated contacts 54 and 55 to lift the arm 25 70 against gravity and the spring 71, so as to break contact between the contacts 16 and 17 so that the paths to the coils of 60, 24, 29, and 20 are broken and both whistles 63 and 26 are blown the miniature signal 28 raised 30 to the on or danger position and the motive power of the train shut off, or brakes applied or both.
- It is therefore evident that provision is made against such failure of apparatus as 35 will cause the current to differ from the predetermined normal strength.
- Fig. 2 shows the connexion relating to one complete section AB at one end A of which are placed a warning contact 1 and two stop contacts 2 and 3 and at the other end B a warning contact 6 and two stop contacts 5 and 4. The two ends A and B respectively have also switching instruments X and Y. When the switching instrument X is set 40 to danger, its armature 73 is in the position hereinafter referred to as the "open" position (indicated in the drawings by the word "open") and makes contact with the contacts 75 and 76, whilst when the instrument X is set to line-clear its armature 73 is in the position hereinafter referred to as the "closed" position (indicated in the drawings by the word "closed") and is in contact with the contact 79 and the contact plate 81 45 which is carried by but insulated from the armature 73, is in contact with the contact 83. The armature 74 of the switching instrument Y makes contact with the contacts 78 and 77 in the "open" position and with the contacts 80 and by means of its insulated contact plate 82 with the contact 84 in the "closed" position. There are also resistances 50 85, 86, 87 and 88 in the instrument X and 89, 90, 91, and 92 in the instrument Y connected as shown and double pole three-way
- switches 250 and 251 at the ends A and B of the section respectively.
- By the use of the switch 250 or 251 the signalman at the end A or B of the section is enabled to control the traffic passing over this section—that is to say, he is enabled to prevent a train having thereon apparatus such as above described with reference to Figure 1 from entering or from leaving the section at his end or to allow it to enter the section or to leave it at his end. The normal position is as shown in the figure the connexions with the track contacts 1, 2, 6, and 5 being broken and as hereinafter described no train being able to enter or leave the section.
- To allow a train to enter the section it is essential that the switch 250 or 251 at the entering end should be moved to make the correct up or down road as otherwise a train would as hereinafter described, be unable to obtain clearance when entering the section. As hereinafter explained it is immaterial whether the switch 250 or 251 is moved into the position to allow a train to enter the section if another train is already in the section, for in this case the section is already blocked as hereinafter described and the signalman is powerless to admit another train.
- It is therefore evident that though the signalman can exercise a selective control over the traffic, error on his part does not introduce any danger of collision.
- The operations performed by the train in its passage through the section on the down and up journeys will now be described.
- When a train running on the down journey—that is to say, in the direction indicated by the word "down" and an arrow in Fig. 2—has to pass over the section AB, and permission has been obtained by the signalman at A from the signalman at B to allow that train to enter this section at the end A, the switches are moved by the signalmen at A and B into the position for the down journey—that is to say, towards the right.
- When the line is clear and the switches 250 and 251 are moved into the positions for the down journey, and a train running on the down journey interacts with track contact 1 current from the generator 32 flows through the shoe 10 as before described to track contact 1 wire 254 contacts 252 and 253 of the switch 250 to wire 72 contacts 83 and 81 wire 93 resistance 89 wire 94 to the coil 95 of the polarized switching instrument Y to earth thence by wire 99 to the rails to the frame of the locomotive and back to the generator as hereinbefore described.
- The direction of the current through the coil 95 is such that the armature 74 is moved into the "open" position. The coil 95 is thus connected in parallel with the resist-

ance 90 by wire 102 contact 78 armature 74 and earth. The values of the resistances 89 and 90 are so related to that of the resistance of the coil 95 that the combined resistance of these resistances and the coil 95 as thus arranged is such as to cause a current of the predetermined normal value to flow from the generator 32 through the coils of the electromagnet 34. The armature 52 is thus attracted to complete the alternative circuits of the coils of the solenoids 24 and 20 and magnet 29 the warning operation is restrained and the line clear whistle is blown.

15 The current also initially travels through
the following parallel path:—the resistance
91, contact 80, and armature 74. Initial
paralleling of this kind may be disregarded
in all cases where the continued passage of
20 current from the train switches out the said
parallel path, as the arrangement is such
that a train is able to complete a switching
operation from a track contact before the
restraint on the warning or stopping appa-
25 ratus effected by the contacting device is re-
moved, so that the strength of the current
produced by the initial paralleling is of no
consequence, except in so far as the resist-
30 ance of the track portion of the circuit pro-
duced by this paralleling is, as hereinafter
indicated, different from the resistance pro-
duced when the armature has been correctly
35 switched over, so that if the armature fails
to be moved when required, a warning or
stopping operation is produced as above
described.

When the locomotive running on the down journey interacts with the stop contact 2 current from the generator 32 flows through the shoe 10 track contact 2 wire 255 contacts 256 and 257 of the switch 250 wire 72 and thence as before described with reference to track contact 1. In this way the location of the armature 74 in the "open" position from track contact 1 is checked.

Should the armature 74 not contact with contact 78 to complete the circuit of the resistance 90 when the train is on either track contact 1 or 2 current of a predetermined normal value will not flow through the coils of electromagnet 34 and warning and stopping operations will be effected on the train.

55 The contacts 82 and 84 are thus disconnected and any other train interacting with track contact 5 or 6 is unable to obtain clearance and cannot enter the section at the end B.

When the locomotive on the down journey interacts with track contact 3 current flows as before from the generator 32 to the shoe 10 through track contact 3, resistance 85 the coil 97 of the polarized switching instrument X and by wire 99 and the rails to the frame of the locomotive and back to the gen-

erator as hereinbefore described. The armature 73 is moved into the "open" position to contact with contact 75 and the coil 97 is connected in parallel with the resistance 87 by contact 75 armature 73 and the rails. 70 The values of the resistances 85 and 87 are so related to that of the resistance of the coil 97 that the combined resistance is such that predetermined normal current will flow from the generator 32 through the coils of the electromagnet 34. Warning and stopping operations are thus restrained and a line-clear intimation is given as previously described. Should the armature 73 not contact with contact 75 to complete the circuit of resistance 87 current of a predetermined normal value will not flow from the generator 32 through the coils of electromagnet 34 and warning and stopping operations will be performed upon the train. 85

The train has now passed completely within the section and has caused the disconnection of the contacts 82 and 84 and of the contacts 81 and 83 at the two ends of the section respectively thus preventing the entrance of another train at either end into this section regardless of the setting of the switches 250 and 251. 90

When the locomotive continuing on the down journey interacts with track contact 4, current flows as before from the generator 32 to the shoe 10 track contact 4 thence by wire 105 to the coil 96 of the polarized switching instrument Y wire 106 to the rails to the frame and back to the generator as hereinbefore described. The armature 74 is moved into the "closed" position and normal current flows from the generator 32 through the coils of electromagnet 34 and a line-clear intimation is given and the warning and stopping operations on the train are restrained.

When the train interacts with track contact 5 current from the generator 32 flows as before through the shoe 10 track contact 5 wire 258 contacts 259 and 260 of the switch 251 resistance 261 wire 106 to the rails and to the frame of the locomotive. Predetermined normal current thus flows through the electromagnet 34 and the warning and stopping operations are restrained and the line clear intimations effected. 110 115

When the train interacts with track contact 6 the current from the generator 32 flows as before through the shoe 10 track 120 contact 6 wire 262 contacts 263 and 264 of the switch 251 wire 103 contacts 84 and 82 wire 104 to the coil 98 of the polarized switching instrument X to earth wire 106 125 the rails and frame of the locomotive and back to the generator 32 as previously described. The resistance 86 is switched into parallel circuit, and the current is consequently caused to be of predetermined normal strength. 129

It will thus be seen that unless the armature 74 has been moved so as to bring the contact 82 into contact with contact 84 this circuit will not be completed. The armature 73 under the influence of the coil 98 is moved to close the contacts 83 and 81 and the train passes out of the section having left both armatures 74 and 73 in the "closed" position thus leaving the section clear for another train to enter.

When a train running on the "up" journey (that is to say, in the direction indicated by the word "up" and an arrow in Fig. 2) has to pass over the section AB, and permission has been obtained by the signalman at B from the signalman at A to allow that train to enter the section at the end B, the switches 250 and 251 are moved by the signalmen at A and B to the position for the up journey that is to the left and the following operations are performed.

When the train interacts with track contact 6 current flows from the generator 32 by wire 33 (Fig. 1) the coils of electromagnet 34 wire 35 arm 36 contact 37 of the commutator switch 100 wire 42 arm 43 contact 44 of the reversing gear switch (which is now moved over to allow the train to run on the up journey, the commutator switch 100 being still in the position shown in the figure) wire 49 the frame and rails wire 106 earth coil 98 of the polarized switching instrument X wire 104 contacts 82 and 84 (which are closed if the section is clear) wire 103 contacts 265 and 263 of the switch 251 wire 262 track contact 6 shoe 10 wire 48 wire 107 resistance 64 contacts 47 and 45 of the reversing gear switch 41 wire 50 contact 39 and arm 38 of the commutator switch 100 wire 51 to the generator 32.

It will thus be seen that since, by reason of the change of connections effected by the moving over of the reversing gear switch, the direction of the current through the coil 98 is opposite to that of the current flowing when the train interacts with the track contact 6 when it is travelling in the down direction the armature 73 is moved into the "open" position to contact with contacts 75 and 76. The resistance 88 is thus connected in parallel with the coil 98 by the armature 73 and contact 76.

The combined value of the resistance of the coil 98 and resistance 88 thus connected is less than the value of the resistance presented by the track portion of the circuit when the armature 73 is moved into the "closed" position when operated by the train running out of the section on the down journey, by the value of the resistance 64 placed in circuit by the reversing gear switch.

By the insertion therefore of this compensating resistance 64 (or 65 when the commutator switch 100 is operated) current

of a predetermined normal value is caused to flow through the coils of electromagnet 34 and a line clear intimation is given and warning and stopping operations are restrained.

When the locomotive interacts with track contact 5 current from the generator 32 flows through the frame and rails wire 106 earth the coil 98 of the polarized switching instrument X wire 104 contacts 82 and 84 wire 103 contacts 266 and 259 of the switch 251 wire 258 track contact 5 the shoe 10 and the apparatus on the locomotive. The armature 73 is thus maintained in the "open" position and the resistance 88 is maintained in parallel circuit.

Should the armature 73 not contact with contact 76 and so bring the resistance 88 into the circuit current of a predetermined normal value will not flow through the coils of electromagnet 34 and warning and stopping operations respectively will be effected on the train, when it interacts with the track contacts 6 and 5.

The contacts 81 and 83 are thus opened and any other train interacting with track contacts 1 and 2 is unable to obtain clearance and cannot enter the section at that end.

When the locomotive continuing on its up journey interacts with track contact 4 current flows as before from the generator 32 through the coils of electromagnet 34 the frame and rails wire 106 coil 96 of the polarized switching instrument Y wire 105 track contact 4 and shoe 10 returning to the generator 32 through the compensating resistance 64 or 65 and wire 51. The current through the coil 96 is thus in the direction opposite to that in which it flowed when the train on its down journey interacted with track contact 4 and the armature 74 is moved into the "open" position to contact with contacts 77 and 78. A parallel path is thus completed to that of the coil 96 through armature 74 contact 77 and resistance 92. Normal current thus flows through the coils of electromagnet 34 a line-clear intimation being given and warning and stopping operations restrained. Should however the armature 74 not contact with contacts 77 so as to bring into the circuit the resistance 92 current of a predetermined normal value will not flow through the coils of electromagnet 34 and the warning and stopping operations will be effected on the train.

Thus it will be seen that the train on entering the section and interacting with track contacts 6, 5, and 4 is unable to proceed unless it has moved both armatures 73 and 74 into the "open" position and thereby rendered the track contacts 1 and 2 at the end A and 6 and 5 at the end B of the section non-conductors so that the en-

trance of another train into the section is prevented regardless of the position of the switches 250 and 251.

When the train continuing on the up journey interacts with track contact 3 current flows as before from the generator 32 through the coils of electromagnet 34 to the frame and rails wire 99 coil 97 of the polarized switching instrument X resistance 85 track contact 3 shoe 10 compensating resistance 64 or 65 and back to the generator 32. The current through the coil 97 is thus in the direction opposite to that in which it flowed when the train on its down journey interacted with track contact 3 and the armature 73 under the influence of coil 97 is moved into the closed position to contact with contact 70 thus bringing into the circuit the resistance 86 and so causing current of the predetermined normal value to flow through the coils of electromagnet 34. Should the armature 73 not contact with contact 79 to complete the circuit of resistance 86 current of a predetermined normal value will not flow through the coils of electromagnet 34 and warning and stopping operations will be performed.

When the locomotive continuing on the up journey interacts with track contact 2 current from the generator 32 flows as before described through the coils of electromagnet 34 the frame and rails wire 99 resistance 268 contacts 269 and 256 of the switch 250 wire 255 track contact 2 shoe 10 and compensating resistance 64 or 65.

The resistance 268 is less than the resistance 261 by the value of the compensating resistance 64 or 65 and is such that in combination with the resistance 64 or 65 it will cause current of a predetermined normal value to flow through the coils of electromagnet 34 so that a line clear intimation will be given and the warning and stopping options will be restrained. It will thus be seen that had the switch 251 been set in the down position for a train running on the up journey the resistance of the track portion of the circuit from track contact 5 through the resistance 261 would have been greater in value than the normal resistance by the value of the compensating resistance 64 or 65. Thus current of predetermined normal value would not flow through the coils of electromagnet 34 and a train would be warned and stopped on track contact 5.

Conversely had the switch 250 been moved into the up position and a train running on the down journey interacted with track contact 2 the resistance of the track portion of the circuit through track contact 2 through resistance 268 would have been less than normal by the value of the compensating resistance 64 or 65 and current of a predetermined normal value would not flow through the coils of electromagnet 34 and

a warning and stopping operation would be performed on the train.

When the train interacts with track contact 1 before passing out of the section current flows as before from the generator 32 through the coils of electromagnet 34 the frame and rails wire 99 to earth coil 95 of the polarized switching instrument Y wire 94 resistance 89 wire 93 contacts 81 and 83 wire 72 contacts 267 and 252 of the switch 250 wire 254 track contact 1 shoe 10 compensating resistance 64 or 65 and back to the generator 32. The direction of the current through the coil 95 is thus opposite to that of the current which flowed when the train on its down journey interacted with track contact 1 and the armature 74 under the influence of coil 95 is moved into the closed position to contact with contact 80 thus bringing the resistance 91 into the circuit at contact 80. Normal current is thus caused to flow through the coils of the electromagnet 34 a line clear intimation is given and warning and stopping operations are restrained.

It will be seen that this circuit is not completed unless the contacts 83 and 81 have been closed when the locomotive interacted with track contact 3 when running on the up journey. Moreover should the armature 74 not bring the resistance 91 into the circuit at contact 80 current of a predetermined normal value would not flow through the coils of the electromagnet 34.

It will thus be seen that by the use of the switches 250 and 251 the signalmen at A and B are able to control the entrance or exit of any train at their particular ends of the section and moreover that should improper use be made of these switches in certain cases, as for example should the switch 250 be moved into the up position to allow a train running on the down journey to enter the section at the end A or should the switch 251 be moved into the down position to allow a train running on the up journey to enter the section at the end B the trains would be warned and stopped and traffic delayed. If desired the switches 250 and 251 may be spring controlled so as always to take up the "blocked" positions as shown in the figure and in this case the signalmen at A and B will have to hold them over in the required positions until the train has passed over the track contacts to which they relate. Then on releasing the switches 250 and 251 they will always take up their normal or blocked position.

It will be seen that if a train passing out of a section is in contact with the last track contact 6 thereof at the same time as another train entering the same section is in contact with the first track contact 1 thereof, the train leaving the section will first free

- the section by operating the instrument X at the entering end of the section so as to give the entering train clearance and the entering train will then set the instrument 5 Y so as to block the section and so cause the train which is leaving the section to receive a warning. The last mentioned train will thus receive an automatic signal that another train is following it up closely.
- 10 Each of the armatures of the polarized relays hereinbefore described is adapted to remain in the position into which it is switched when a train makes contact with a track contact, until the polarized relay in 15 question is so traversed by current as to reverse the position of the armature.
- It is obvious that the arrangement should be such that a train is able to complete a switching operation from a track contact 20 before the restraint of the warning and stopping apparatus is removed by the contacting device.
- It is intended for the purpose of these improvements that sections of track should 25 overlap or intersect each other in the manner described in the application for Letters Patent No. 625,475 of 1910 or in the manner described in the specification of application for Letters Patent No. 761,042, of even date 30 herewith.
- In order to protect a train when just entering a stretch of track provided with train 35 protecting apparatus according to this invention from the possibility of its being run into by a following train it is intended that the train shall be otherwise protected as by means of interlocked signals or the like when entering on a terminal section until it has proceeded sufficiently far along that section 40 to be properly protected by the train protecting apparatus relating to the stretch of track in question. At a terminal section the contacts 1, 2, 3, at the entering end of the section are preferably followed closely by the 45 corresponding contacts of the intersecting section in order that a train entering the system may as soon as possible obtain full protection of the system as it will as soon as it has passed over a sufficient distance beyond 50 the entering contacts of the first intersecting section to cause a train following it to be stopped automatically by the entering contacts of the terminal section before colliding with the train that has first entered the 55 system even if the last mentioned train be stopped after travelling over the said sufficient distance; consequently it is advisable to extend the protection afforded, by means such as interlocking signals so that any 60 train entering the stretch of track is protected thereby until it has traversed the aforesaid sufficient distance beyond the entering contacts of the first intersecting section.
- The means for applying the brakes on the train consists preferably of one or more cylinders provided with one or more pistons or the like suitably connected with the lever or the like by which the brakes on the train are applied the arrangement being such that upon failure of the electrical restraint on the movement of a valve fluid pressure will be caused to act on the piston or pistons so that the brakes are applied on the train. Each train should be fitted with continuous 75 automatic brakes.
- The means for shutting off the motive power by which the train is driven may be arranged in a manner similar to that mentioned above for applying the brakes or, if desired, the brakes may be applied and the power of the train shut off by means of only one cylinder and piston or the like.
- Various modifications may be made in the apparatus without departing from the scope 85 of the invention. For example, wherever suitable, rails or other metallic conductors may be substituted for earth conductors and vice versa also other metallic conductors 90 may be substituted for rails.
- It will be obvious that parts of the apparatus described herein may in some cases be multiplied or omitted.
- What I claim and desire to secure by Letters Patent of the United States is:— 95
1. A train protecting device comprising warning and stopping means on the train, solenoids controlling the action of the said warping and stopping means, a source of energy operatively connected to the solenoids, a train contact operatively connected to the source of energy and adapted to disconnect the latter from said solenoids when displaced, track contacts coacting with the train contact, a second source of energy, an electromagnet operatively connected to the second source of energy, an armature coacting with the electromagnet and adapted to break the circuit comprising the first source of energy and the solenoids controlling the warning and stopping means and to introduce a substitutional circuit when the train contact has been displaced and the track is in a clear condition, a manually operated commutator switch operatively connected to the second source of energy, and a compensating resistance designed to be switched into the circuit including the second source of energy and the electromagnet when the train has been 110 reversed on a loop or the like. 115
2. A train protecting device comprising warning and stopping means on the train, solenoids controlling the action of the said warning and stopping means, a source of electrical energy connected to the solenoids, a train contact operatively connected to the source of energy and adapted to disconnect 125

the latter from said solenoids when displaced, track contacts coacting with the train contact, a second source of energy, a commutator switch connected to the second 5 source of energy and designed to be simultaneously actuated with the reversing gear of the train and so caused to reverse the direction of flow of current through the train apparatus, a compensating resistance 10 adapted to be switched into the circuit including the second source of energy, and means in circuit with the second source of energy for forming a substitutional circuit through the solenoids and first source of 15 energy when the train contact has been displaced and the track is in a clear condition.

3. Electrical train-controlling apparatus comprising train apparatus carried by a train and including an electro-responsive 20 device whose movable portion is adapted to occupy a line-clear or a danger position according to the condition as to energization of said electro-responsive device and including also a direction-corresponding part 25 adapted to occupy different positions in accordance with opposite directions of running of the train, and means on the track adapted to occupy different positions according to the directions in which a train is 30 to be allowed to run, said direction-corresponding part and said means on the track being adapted to cause and control the passage of electricity to said electro-responsive device and thereby, but only in the case of 35 correspondence between their positions, to cause a condition as to energization of said electro-responsive device corresponding to the line-clear position of said movable portion.

4. Electrical train-controlling apparatus comprising train apparatus carried by a train and including an electro-responsive device whose movable portion is adapted to occupy a line-clear or a danger position according to the condition as to energization 45 of said electro-responsive device and including also a direction-corresponding part adapted to occupy different positions in accordance with opposite directions of running of the train, and means on the track adapted to occupy different positions according to the directions in which a train is to be allowed to run, said direction-corresponding part and said means on the track 50 being adapted to cause and control the passage of electricity to said electro-responsive device and thereby, but only in the case of correspondence between their positions, to cause a condition as to energization of 55 said electro-responsive device corresponding to the line-clear position of said movable portion, said means on the track being adapted to cause electricity to pass differently through said train apparatus according 60 to the positions of said means on the track 65

corresponding to opposite directions of running, and said direction-corresponding part being adapted to produce the adjustment necessary for causing the appropriate condition as to energization of said electro-responsive device on account of the difference thus produced by said means on the track. 70

5. Electrical train-controlling apparatus comprising on a train apparatus including an electro-responsive device whose movable portion is adapted to occupy a line-clear position when said electro-responsive device is energized, and on the track electro-responsive traffic-controlling devices, track contacts corresponding to said traffic-controlling devices, means for enabling signalmen to connect said traffic-controlling devices with said corresponding track contacts and thereby to cause the condition as to energization of said electro-responsive device on said train when said train is in contact with said track contacts to be dependent on the interaction between said apparatus on said train and said traffic-controlling devices and to disconnect said traffic-controlling devices from said corresponding track contacts and thereby to cause said electro-responsive device on said train when said train is in contact with said track contacts to be de-energized independently of the condition of said traffic-controlling devices. 75 80 85 90 95 98

6. Electrical train-controlling apparatus comprising on a train an electro-responsive device whose movable portion is adapted to occupy a line-clear or a danger position in accordance with the strength of current traversing said electro-responsive device, a train circuit portion including said electro-responsive device, and direction-corresponding means adapted to occupy different positions in accordance with opposite directions of running of said train and accordingly to cause said circuit portion to have two different resistances, and on the track a track contact, conductive means adapted to form a closed circuit with said train circuit portion when said train is in contact with said track contact, and traffic-controlling means adapted to control the direction of running of said train over said track contact by causing the track portion of the circuit so completed to have one resistance if it is intended that trains should travel in one 100 105 110 115 120 125 130 direction over said track contact and another resistance if it is intended that trains should travel in the opposite direction over said track contact, the resistances of said train and track circuit portions being such as to cause the current flowing through said circuit to be of the strength necessary to cause the movable portion of said electro-responsive device to occupy the line-clear position only in the case of correspondence 130

between the positions of said direction-corresponding means and said traffic-controlling means.

7. Electrical train-controlling apparatus comprising on a train an electro-responsive device whose movable portion is adapted to occupy a line-clear or a danger position in accordance with the strength of current traversing said electro-responsive device, a train circuit portion including said electro-responsive device, and direction-corresponding means adapted to occupy different positions in accordance with opposite directions of running of said train and accordingly to cause said circuit portion to have two different resistances, and on the track a track contact, and direction-determining means for enabling a signalman to form a closed circuit with said train circuit portion when said train is in contact with said track contact and to cause the track portion of the circuit so completed to have one resistance if it is intended that trains should travel in one direction over said track contact and another resistance if it is intended that trains should travel in the opposite direction over said track contact, the resistances of said train and track circuit portions being such as to cause the current flowing through said circuit to be of the strength necessary to cause the movable part of said electro-responsive device to occupy the line-clear position only in the case of correspondence between the positions of said direction-corresponding means and said direction-determining means.

8. Electrical train-controlling apparatus comprising on a train an electro-responsive device whose movable portion is adapted to occupy a line-clear position only when the strength of the current energizing said electro-responsive device is between predetermined upper and lower limits, a train circuit portion including said electro-responsive device, and direction-corresponding means adapted to occupy different positions in accordance with opposite directions of running of said train and accordingly to cause said circuit portion to have two different resistances, and on the track a track contact, conductive means adapted to form a closed circuit with said train circuit portion when said train is in contact with said track contact, and traffic-controlling means for causing the track portion of the circuit so completed to have one resistance if it is intended that trains should travel in one direction over said track contact and another resistance if it is intended that trains should travel in the opposite direction over said track contact, the resistances of said train and track circuit portions being such as to cause the strength of the current flowing through said circuit to be between said predetermined upper and lower lim-

its only in the case of correspondence between the positions of said direction-corresponding means and said traffic-controlling means.

9. Electrical train-controlling apparatus comprising on a train an electro-responsive device whose movable portion is adapted to occupy a line-clear position only when the strength of the current energizing said electro-responsive device is between predetermined upper and lower limits, a train circuit portion including said electro-responsive device, and direction-corresponding means adapted to occupy different positions in accordance with opposite directions of running of said train and accordingly to cause said circuit portion to have two different resistances, and on the track a track contact, and direction-determining means for enabling a signalman to form a closed circuit with said train circuit portion when said train is in contact with said track contact and to cause the track portion of the circuit so completed to have one resistance if it is intended that trains should travel in one direction over said track contact and another resistance if it is intended that trains should travel in the opposite direction over said track contact, the resistances of said train and track circuit portions being such as to cause the strength of the current flowing through said circuit to be between said predetermined upper and lower limits only in the case of correspondence between the positions of said direction-corresponding means and said direction-determining means.

10. Train-controlling apparatus comprising a direction-corresponding means carried by a train adapted to occupy different positions in accordance with the opposite directions of running of said train and, for controlling the passage of trains at the two ends respectively of a section of track, two electromagnetic traffic-controlling devices each of which is adapted in accordance with two conditions as to electrification to cause its movable part to occupy a line-clear position and a danger position respectively and thus to control the passage of trains over the corresponding end of said section, a first track contact at each end of said section adapted to be operatively connected by the said traffic-controlling device pertaining to the same end of said section to the said traffic-controlling device pertaining to the other end of said section only if the movable part of the former traffic-controlling device is in the line-clear position, and a second track contact at each end of said section so placed as to be encountered after said first track contact by a train entering said section at the corresponding end of said section and operatively connected to the traffic-controlling device pertaining to the same

end of said section, said direction-corresponding means being adapted on contact of said train with said first track contact on entering said section at either end thereof to 5 cause the condition as to electrification of the said traffic-controlling device pertaining to the other end of said section to be such as to cause its movable part to occupy the danger position and on leaving said section 10 over said first track contact at either end of said section to cause the condition as to electrification of the said traffic-controlling device pertaining to the other end of said section to be such as to cause its movable 15 part to occupy the line-clear position and on contact of said train with said second track contact on entering said section at either end thereof to cause the condition as to electrification of the said traffic-controlling device pertaining to the end of said section at which the train is located to be such as to cause its movable part to occupy the danger position and on leaving said section over said second track contact at either 20 25 end of said section to cause the condition as to electrification of the said traffic-controlling device pertaining to the end of said section at which the train is located to be such as to cause its movable part to occupy the line-clear position.

11. Train protecting apparatus compris-

ing on the track an electro-responsive device whose movable part is adapted to occupy two different positions in accordance with the directions of current energizing said 35 electro-responsive device and on a train an electro-responsive device whose movable part is adapted to occupy a line-clear position only when current of a predetermined strength energizes said electro-responsive device on said train, a generator of electricity, electrical connections including said electro-responsive device on said train and said generator of electricity, and direction-corresponding means adapted to occupy different 40 positions in accordance with the opposite directions of running of said train and thereby so to change said electrical connections as to cause currents to flow in opposite directions through said electro-responsive device on the track, the movable part of said electro-responsive device on the track and said direction-corresponding means being adapted, only when occupying mutually corresponding positions, to cause said electro-responsive device on the train to be energized by current of said predetermined 45 strength.
